SORTING APPARATUS

John W. Whitson, New York, N. Y., assignor of
one-half to Clare H. Whitson, New York, N. Y.

Application February 15, 1950, Serial No. 144,281

7 Claims. (Cl. 211—10)

1

My invention relates to improvement in sorting apparatus for the sorting of time cards, coupons, bank checks and other media used in compiling statistics.

The object of my invention is to provide a series of receptacles for the reception of such media and to condense such receptacles into a smaller space than has heretofore been possible. My invention provides for the opening and closing of the receptacles by finger tip control, provision being made for varying the depth of the receptacles to facilitate the handling of varying sizes of media used in compiling statistics.

Further objects of my invention will appear from the detailed description of the same hereinafter.

While my invention is capable of embodiment in many different forms, for the purpose of illustration I have shown only certain forms of the same in the accompanying drawings, in which—

Fig. 1 is a front elevation of the apparatus.

Fig. 2 is a front elevation of a primary element.

Fig. 3 is a front elevation of a series of secondary elements.

Fig. 4 is a front elevation of a secondary element of a different formation from that of Fig. 3.

Fig. 5 is a longitudinal cross-section of the apparatus taken on line 5—5 of Fig. 1, showing only the primary elements in position.

Fig. 6 is a side elevation of the upper locking member of a partition.

Fig. 7 is an end elevation of the same.

Fig. 8 is a side elevation of the lower spacing member of a partition.

Fig. 9 is an end elevation of the same.

Fig. 10 is a perspective view of the front end of the apparatus.

Fig. 11 is one example of a sortable medium.

Fig. 12 is a diagram illustrating a step in the operation of the apparatus.

In the drawings I have shown a casing 1 with a bottom or floor 2 and side walls 3 and 3'. A plurality of longitudinal extending partitions 4 are positioned laterally in the casing, each partition has a lower spacing member 5 with spaced openings 6 formed in the bottom edge thereof and an upper U-shaped locking member 7. A plurality of primary sorting elements 8 are movably held in the openings 6 so as to be readily tilted toward the front or the rear of the apparatus thru pressure on a finger member 8'. The partitions are received in openings 9 of the primary sorting elements, the lower spacing member is inserted thru an aligned series of the openings 9 and then its locking member 7 is inserted thru

the same openings and rivets or screws 10 are inserted thru openings 11 and 11' to lock the assembly together, the openings 11 and 11' are in alignment when the members 5 and 7 are assembled. With all of the partitions 4 thus in place the entire assembly of partitions and primary sorting elements is placed in the casing over an assembly of members 12 which enter openings 14 of the primary sorting elements 8. The members 12 are fastened to cross members 13, the ends of which are each bent upwardly and formed into a loop to fit around a vertical post 16, the loop fitting between two knurled lock nuts 17. The posts 16 are bolts and are screwed thru the bottom 2 of the casing; the bolt heads serve as feet for the apparatus as illustrated at 16'. The assembly of members 12 and 13 forms a movable floor or support means which can be raised or lowered thru movement of the lock nuts 17.

The movable floor increases the utility of my invention in that the apparatus will accommodate itself to varying sizes of sortable media and each size of media when sorted into the apparatus will be in substantially the same relative position to the upper margins of the sorting elements for easy removal from the apparatus. Thus, my invention can be used with different sizes of sortable media and one size of media is as readily removable from the apparatus as another size.

At each end of the locking members 7, of the partitions 4, is an opening 18 for the reception of a rod 19 which is passed there-thru and fastened into the side walls 3 and 3' of the casing 1.

Secondary sorting elements 20 and 21 each have a series of openings 22 to receive the partitions 4 and a series of openings 23 to receive the floor members 12.

Sets of the secondary sorting elements are placed between the primary elements as illustrated in Fig. 10, there being a secondary sorting element 21 back of each secondary element 20. Each set of the secondary sorting elements 20 has a finger member 20' for tilting the elements towards the front or rear of the apparatus thru finger pressure against the finger members. The members 20' of a set are in off-set relation to each other as illustrated in Fig. 3 and are marked with the numerical digits 0 to 9 as illustrated. Secondary sorting elements 20 are also marked adjacent their upper edges with the numerical digits 0 to 4 inclusive as illustrated at 24, Fig. 3, and secondary sorting elements 21 are marked thus with the numerical digits 5 to 9 inclusive as illustrated at 25, Fig. 4. These markings serve

to identify one thousand of the receptacles 26, Fig. 10, formed by the sorting elements in combination with the partitions. The receptacles at the left have no identifying numbers.

All of the sorting elements have their left-hand marginal edges cut at an angle as illustrated at 27 and the lower edges of all of the elements rest on the bottom 2 of the casing 1.

The finger members 8' of the primary sorting elements are in alignment with each other and are marked with the numerical digits 0 to 9 inclusive, except the rearmost element which has no identifying digit. Indication of these markings is shown by the numbers enclosed in circles at the top of Fig. 5.

The secondary sorting elements have projections formed in their surfaces adjacent their upper margins as illustrated at 28, to serve as an arresting means and stop the upward movement of sortable media that is composed of material too light to provide sufficient weight for the media to remain at the bottom of the receptacles 26 thru the action of gravity. The movement forward and backward of the sorting elements tends to cause an upward movement of the media and project the media above the upper margins of the sorting elements; the projections 28 arrest this movement. The projections 28 may be in the form of wire staples as illustrated.

The sorting elements may be formed from any suitable sheet material.

The primary sorting elements may have the numerical digits 5 to 9 inclusive marked on them so that they may serve the purpose of a secondary element 21.

The primary sorting elements form a support means for the secondary sorting elements, the primary elements serving to support each of the sets of secondary elements when they are tilted towards the front or rear of the apparatus.

The sorting elements form the front and rear walls of the receptacles 26.

The sorting elements fit loosely over the partitions 4 so that the sorting elements may be freely moved forward and backward in the casing 1.

The lock nuts 17 and projections 28 may be omitted and handles 31, as indicated in dotted lines, Fig. 5, may be fastened to cross members 13; the purpose of the handles being to raise the members 12 and cause them to move upwardly sortable media, such as bank checks, and cause the media to be partially projected above the sorting elements so that the said media may be more easily removed from the apparatus.

The sorting elements may be spaced apart by the formation of projections as illustrated at 32 and 32', Fig. 4, so as to increase the distance between the sorting elements and thus provide a receptacle 26 whose front to back depth would be as determined by the projections. Projections may be formed in or fastened on any of the sorting elements as desired; those illustrated at 32 are pressed outwardly from the front face of an element 21 and those illustrated at 32' are pressed outwardly from the rear face of the element.

Operation

Suppose that it is desired to sort a series of coupons 29, Fig. 11. The coupons are first sorted into groupings by their thousands digit.

With the sorting elements tilted toward the rear of the apparatus, the primary sorting element, whose number corresponds with the hundreds digit of the coupon to be sorted, is moved

5 by finger pressure on its finger member 8' toward the front of the apparatus causing an increase in the top distance between this primary sorting element and the next rearmost primary sorting element. Next the secondary sorting element 20 whose number corresponds with the tens digit is moved, by finger pressure on its finger number 20', to a vertical position. This opens 10 two series of receptacles 26 and exposes their numbers as at 24 and 25 as illustrated in Fig. 10, the coupon is then dropped into the receptacle whose number corresponds to the units digit of the coupon. For example, to sort the coupon of Fig. 11, by its account number 1024, the coupon is picked up with one hand and the fingers 15 of the other hand are used to operate the apparatus; then primary sorting element whose finger member 8' is marked 0 (which corresponds with the hundreds digit of the coupon account number) is moved to its forward position as illustrated in Fig. 10; next the secondary sorting element whose finger member 20' is marked with the digit 2 (which corresponds with the tens digit of the coupon account number) is moved to a substantially vertical position to open 25 two series of the receptacles 26 and exposing their numbers to view as at 24 and 25, Fig. 10; the coupon is then dropped into receptacle number 4 (which number corresponds with the units digit of the coupon account number) as illustrated in dotted lines at 29', Fig. 10. The foregoing is followed until all of the coupons of a series have been sorted into the apparatus whence 30 they may be removed positioned in numerical sequence. Several coupons of a like account number may be sorted into a single receptacle 26.

Since some of the coupons will rest against the back of the secondary sorting elements when the apparatus is opened, it is necessary to provide 40 that all of the coupons will rest in a backwardly inclined position when it is desired to examine the coupons while they are still sorted into the apparatus. With all of the sorting elements inclined toward the rear of the apparatus, each secondary sorting element is raised in turn and its bottom margin is positioned against the next rearwardly positioned sorting element, as illustrated in Fig. 12, so as to hold the coupons pressed against the rearward sorting element in which position the coupons may be readily examined. The openings 22 and 23 in the secondary sorting members serve to facilitate the foregoing described operation and in combination with their associated element provide a means for accomplishing the same.

When it is desired to replace a coupon, which has been sorted into the apparatus, with a coupon of a higher number, the sorting procedure is as follows: With the coupon 29 of Fig. 11 in its position 29' in the apparatus, then when coupon number 4 of this account number is placed in the apparatus, coupon number 3 is removed from its position and placed in the unnumbered receptacle adjacent to wall 3' at the left of the apparatus as illustrated in dotted lines at 30, Fig. 1. When a series of coupons have been thus sorted the coupons in the receptacle at the left will be in account number sequence when they are removed from the apparatus. The angular margins 27 of the sorting elements expose the upper left-hand corner of the coupons so that they may be easily grasped for removal from the apparatus.

Each set of secondary sorting elements 20 may 75 have their finger members 20' marked as fol-

lows: 0, 10, 20, 30, 40, 50, 60, 70, 80, 90 for the 1st set; 100, 110, 120, 130, 140, 150, 160, 170, 180, 190 for the 2nd set; 200, 210, 220, 230, etc. for the 3rd set; with each of the remaining sets being marked likewise, the 4th set starting with 300, the 5th set with 400, the 6th set with 500, the 7th set with 600, the 8th set with 700, the 9th set with 800 and the 10th set with 900; with the secondary elements marked thus the finger members 8' may be omitted from the primary elements. The apparatus would be used by selecting the secondary element bearing the hundreds and tens digits of the account number of the coupon and then selecting the receptacle according to the unit digit as hereinbefore described.

The apparatus may also be constructed with four of the partitions 4 so as to have five of the receptacles 26 in transverse alignment, in which event the angular edge 27 would be omitted from the sorting elements. Such a modification of the apparatus would be made when it is desired to construct one for, say, sorting bank checks or time cards into numerical order; the checks would be sorted into the apparatus in accordance with the three ending digits of the check or time card number as hereinbefore described in the sorting of coupons.

The apparatus may also be constructed with nine of the partitions 4 so as to have ten of the receptacles 26 in transverse alignment, in which event the secondary sorting elements 21 would be omitted and the secondary sorting elements 20 would be marked at 24 with the digits 0 to 9 to indicate each of the ten receptacles 26.

The apparatus may also be constructed with member 5 having an additional opening "6" formed therein between each of the illustrated openings 6, each of which added openings will receive a secondary element 20 with the openings 9 and 14 (of primary element 8) formed therein instead of the openings 22 and 23 of Fig. 3. With the apparatus thus constructed it may be used as already described for the sorting of media in accordance with three digits and when it is desired to greatly increase the size of the receptacles 26 to accommodate a greater number of, say, time cards, then the secondary elements made as illustrated in Figs. 3 and 4 may be removed from the apparatus in which case the apparatus would have one hundred of the receptacles 26, the primary elements 8 would be suitably marked as hereinbefore described to indicate which of the receptacles 26 they would form. The time cards would be sorted into the apparatus in accordance with their tens and units digits by first selecting the primary element 8 corresponding to the tens digit and then placing the time card in the receptacle in accordance with the units digit. A second sort may then be made in accordance with the hundreds and thousands digits and so on for each pair of digits in the time card number.

While I have described my invention above in detail, I wish it to be understood that many changes may be made therein without departing from the spirit of the same.

I claim:

1. In a sorting apparatus, a casing, a plurality of partitions mounted in said casing, a plurality of selectively tilttable elements positioned transversely of said partitions in fixed spaced relationship to each other, the said elements and

the said partitions forming a plurality of receptacles.

5 2. In a sorting apparatus, a casing, a plurality of partitions mounted in said casing, a plurality of selectively tilttable elements positioned transversely of said partitions and maintained in fixed spaced relationship to each other, the said elements and the said partitions forming a plurality of receptacles, by interlocking openings in the said elements and the said partitions.

10 3. In a sorting apparatus, a casing, a plurality of partitions mounted in said casing, a plurality of selectively tilttable elements positioned transversely of said partitions in fixed spaced relationship to each other, the said elements and the said partitions forming a plurality of receptacles, a movable floor positioned in the said casing and openings in the said elements which openings receive members of the said movable floor.

15 4. In a sorting apparatus, a casing, a plurality of partitions mounted in said casing, a plurality of selectively tilttable elements positioned transversely of said partitions in fixed spaced relationship to each other, the said elements and the said partitions forming a plurality of receptacles, and a movable floor positioned in the said casing and means for moving the said floor.

20 5. In a sorting apparatus, a casing, a plurality of partitions mounted in said casing, a plurality of selectively tilttable elements positioned transversely of said partitions in fixed spaced relationship to each other, the said elements and the said partitions forming a plurality of receptacles for the reception of sortable media and support means for the said media and means to move the first mentioned means.

25 6. In a sorting apparatus, a casing, a plurality of partitions mounted in said casing, a plurality of selectively tilttable elements positioned transversely of said partitions in fixed spaced relationship to each other, the said elements and the said partitions forming a plurality of receptacles for the reception of sortable media and media arresting means formed on a tilttable element.

30 7. In a sorting apparatus, a casing, a plurality of partitions mounted in said casing, a plurality of selectively tilttable elements positioned transversely of said partitions in fixed spaced relationship to each other, the said elements and the said partitions forming a plurality of receptacles, and receptacle size varying means including elements common to all of the said receptacles.

JOHN W. WHITSON.
